[57] CLAIM

The ornamental designs for a multi-stone setting for diamonds and gemstones, as shown and described.

DESCRIPTION

FIG. 1 is a top perspective view of a multi-stone setting for diamonds and gemstones showing my new design;

FIG. 2 is a front elevational view, the rear elevational view being a mirror image;

FIG. 3 is a side elevational view; the opposite side view being a mirror image;

FIG. 4 is a top plan view;

FIG. 5 is a bottom plan view;

FIG. 6 is a top perspective view of a multi-stone setting for diamonds and gemstones showing a second embodiment of my new design;

FIG. 7 is a front elevational view of FIG. 6, the opposite side view being a mirror image;

FIG. 8 is a side elevational view of FIG. 6, the opposite side view being a mirror image;

FIG. 9 is a top view of FIG. 6; and,

FIG. 10 is a bottom plan view of FIG. 6.
